UNITED STATES PATENT OFFICE.

NELSON T. CLINE, OF PITTSBURGH, PENNSYLVANIA, AND FRANCIS E. CLINE, OF INDIANAPOLIS, INDIANA.

AUTOMATIC LUBRICATOR CONTROL.

Application filed September 25, 1920. Serial No. 412,813.

To all whom it may concern:

Be it known that we, NELSON T. CLINE and FRANCIS E. CLINE, respectively, citizens of the United States, and residents of Pittsburgh and Indianapolis, respectively, counties of Allegheny and Marion, respectively, and States of Pennsylvania and Indiana, respectively, have invented a certain new and useful Automatic Lubricator Control; and we do hereby declare that the following is a full, clear, and exact description thereof, reference being had to the accompanying drawings, in which like numerals refer to like parts.

15 This invention relates to lubricator devices such as are commonly associated with fluid compressors and similar power units, including steam driven engines.

The chief object of this invention is to provide in a lubricating system of the character defined valve means which are automatically controlled such that the valve regulates the amount of lubricant supplied to the surface to be lubricated in proportion to the work to be done by the power unit and the amount of lubricant required thereby.

The chief feature of the invention consists in associating with the mechanical valve suitable means which are proportionally actuated by the working or workable fluid.

30 The full nature of the invention will be understood from the accompanying drawings and the following description and claims.

35 In the drawings, Fig. 1 illustrates the invention when applied to a multi-stage air compressor lubricated by the force feed type of system, the control valve embodying the invention being associated with the foregoing. Fig. 2 is an enlarged sectional view of the invention and illustrates the same when associated with a sight feed valve. Fig. 3 is a sectional view taken in planes transverse to the plane of Fig. 2, several of the essential parts lying in different planes, but being sectioned to show their construction more clearly, other parts being shown in elevation for the same purpose.

40 In the drawings the invention is illustrated as applied to a fluid compressor of the multi-stage type wherein 10 indicates the low pressure air cylinder, 11 the high pressure cylinder, and 12 and 13 the prime movers for the multi-stage air compressor illustrated.

45 Associated with the multi-stage air com-

pressor is a force feed lubricating device 14 which is actuated by suitable means not shown, and which forms no part of this invention. 15 indicates the valve means embodying the features of the invention and 60 said valve means is connected with the force feed lubricating device 14 by means of the conduit 16. Similarly, said valve means 15 is connected to the low and high pressure cylinders 10 and 11 respectively by means of 65 the conduits 17 and 18 respectively. All of the foregoing is old in the art and forms no part of the invention. Associated with the valve means 15 is a conduit 19 which preferably, but not necessarily, is connected to the 70 air reservoir or other source of fluid pressure associated with the multi-stage air compressor illustrated.

Figs. 2 and 3 illustrate in detail the construction of the novel valve means, and said figures illustrate the same applied to a sight feed valve. In Fig. 2, 15 illustrates a receptacle, reservoir or chamber forming a body portion enclosing the valve mechanism. As shown in said figures, the reservoir 15 is provided with a cap or cover portion 20 secured to said body portion by means of the bolts 21 and forms a leak-proof joint therebetween by means of suitable packing 22. Upon opposite sides of the reservoir 15, see Fig. 3, 85 there is formed a projecting nipple or plug 23 which communicates with the interior of the reservoir or chamber by means of the channel 24. The exterior of said projection or plug 23 is threaded at 25 and is adapted 90 to receive a cap 26 or a union 27. In the first instance, the cap 26 closes said conduit or channel 24, and in the other instance, the union member 27 secures the conduit 16 to said projection by means of the pipe fitting 95 28, said pipe fitting is preferably tapered at 29 to be seatable at 30 upon the beveled or tapered seat formed upon the projection 23, so that between said parts 23 and 28 there will be a leak-proof joint. The dual means 100 hereinbefore described permits the reservoir or chamber to be connected to the force feed lubricator 14 in the most advantageous manner, since said outlets are interchangeable, and if necessary or desired, both outlets may 105 be connected to the force feed lubricating device 14.

The invention is herein illustrated as applied to a dual control system, but it will be noted that the invention may be applied to a 110

single control or a plural control system without departing from the broader features of the invention. Since the means associated with each of the controls is substantially similar, a description of one will suffice for an understanding of them all. The chamber 15 is provided with an opening 31 which is preferably threaded to receive a combination valve outlet and nozzle member 32, said 10 nozzle being provided with a channel 33, which preferably is enlarged to form a tapered valve seat at 34 communicating with the chamber 15. Positioned within the chamber 15 is a suitable valve member 35 which is complementarily formed so as to be associated with the valve seat 34 and controls the flow of lubricant from the reservoir 15 into the conduit 18, as shown. The means controlling the operation of the valve 35 will 15 be hereinafter described in detail, since the same forms the chief and main feature of the invention.

Lubricant passing through the channel 33 passes through an auxiliary chamber 36 before passing into the conduit 18, and associated with the chamber 36 is the usual sight feed construction, which is as follows: Extending into the chamber 36 is suitable flange means 37 against which abuts a suitable transparent closure member 38, which member is preferably of glass. Associated with the glass closure member 38 is a tapered packing member 39 which is adapted to engage the tapered portion 40 of the glass closure member, and associated with said packing member is a metal washer 41. To secure the glass closure member, yielding packing member and metal washer member in assembled relation to form a leak-proof joint, 30 there is provided a hollow nut 42 externally threaded at 43 and secured to the threaded portion 44 of the chamber forming body 36.

Preferably registering with the opening 31 and the nozzle 32 is an opening 45 in the chamber 36, which opening communicates with the conduit 18 by means of a union 46. This construction with the adjacent tapered faces 47 provides a leak-proof joint. This 40 construction it will be noted, see Fig. 3, permits a socket wrench to be inserted into the opening 45 and chamber 36 to engage the nut portion 48 of the nozzle 32 to screw and secure said nozzle in the threaded opening 31.

Associated with each valve 35 is a stem portion 50, and pivotally supporting the same is an arcuate pressure expandable coil or tube 51, which coil or tube is closed at one end by means of the plug member 52. Said plug member supports the free end of the valve stem 50 by means of the pivot pin 53. The pressure expandable arcuate tube 51 communicates with a header member 54, which header member is rigidly secured to the receptacle or reservoir wall by suitable

means, such as the screws 55. In the present invention, see Fig. 3, two expandable tubes 51 are illustrated and the header member 54 is adapted to simultaneously communicate with both of said tubes, said 70 header member comprises an elongated chamber 56, and preferably integral therewith there is provided a supply conduit 57. At the junction of the supply conduit 57 with the header 54 there is provided a tapered face 58, which tapered face is adapted to bear upon a complementarily formed tapered seat 59 associated with the opening 60 formed in the reservoir wall 15. From the foregoing and from Fig. 3 it will be understood that the header, to which has been secured the several pressure expandable tubes 51 supporting the valves 35, is inserted through the receptacle when the cover cap 20 has been removed therefrom and the conduit or stem portion 57 is inserted through the opening 60 in said reservoir. The washer 61 and nut 62 suitably and rigidly secure said reservoir and header together and form a leak-proof joint between the adjacent faces thereof. Associated with the conduit 57 and communicating therewith is the conduit 19 which as heretofore stated is adapted to be connected to the air reservoir or other source of fluid pressure, said conduits 19 and 57 being provided with complementarily formed tapered surfaces 63 which are secured together by the union member 64 having a threaded engagement with the several parts.

From the foregoing it will be understood that as the pressure in the air reservoir or other source of supply of fluid pressure increases, the same is transmitted through the conduits 19 and 57 to the header chamber 56 and through said chamber to the several arcuate expandable actuating tubes 51 for expanding said tubes. These tubes when subjected to pressure, expand proportional to the pressure in said header and tube, which expansion carries with it the valve 35 to unseat the same from the seat 34, thereby permitting the lubricant in the reservoir 15 to escape into the chamber 36 and conduit 18 communicating therewith through the channel 33. As described and as illustrated in Fig. 3, the escaping lubricant 75 is visible through the transparent closure member 38 of the chamber 36.

In order to limit the unseating movement of the valve 35, means is provided as follows: Said means comprises a threaded bolt member 65, which bolt member has a threaded engagement with the cover cap 20 through the opening 66. Projecting upwardly from the cover cap member and preferably integral therewith and registering with the opening 66 is an annular flange 67 exteriorly threaded, said flange 67 is adapted to receive a threaded cap 68, which

cap is preferably formed with a nut-like head, so that the same may be removed from said annular projection 67. It will be noted that the cap 68 protects the stop and limit bolt 65 from casual injury and also from tampering, since the removal of said cap 68 is necessary before access can be had to the adjustable bolt 65. It will be understood that the unseating movement of the valve 35 is limited by the end of the stem 50 contacting the end of the bolt 65.

The invention claimed is:

1. A lubricating system for a power unit, including a lubricant-containing reservoir, a plurality of means connecting said reservoir with said power unit, a plurality of valve means in said communication for controlling the supply of lubricant thereto, a plurality of pressure expansible means for automatically actuating said plurality of valve means, and a single means connecting said plurality of pressure actuated means to

said power unit for simultaneous and automatic actuation of said expansible means to control said valve.

2. In a forced feed lubricating system for compressors and the like, including means for supplying lubricant to said compressors under pressure, a reservoir between said forced feed supplying means and said compressor, conduit means connecting said reservoir with said compressor, valve means in said conduit, means controlling the flow of lubricant through the same, conduit means connecting said lubricant supplying means and said reservoir, and a plurality of inlets, each adapted to receive and communicate with said last mentioned conduit connecting means.

In witness whereof, we have hereunto affixed our signatures.

NELSON T. CLINE.
FRANCIS E. CLINE.
